UNITED STATES PATENT OFFICE.

CARL FRIEDRICH WILHELM DÖHRING, OF BERLIN, GERMANY.

PRODUCING FIRE-PROOF WALLS AND CEILINGS.

SPECIFICATION forming part of Letters Patent No. 432,023, dated July 15, 1890.

Application filed April 16, 1890. Serial No. 348,200. (No specimens.)

To all whom it may concern:

Be it known that I, CARL FRIEDRICH WILHELM DÖHRING, a subject of the German Emperor, and a resident of Berlin, in the German Empire, have invented certain new and useful Improvements in Producing Fire-Proof Walls and Ceilings, of which the following is a specification.

My invention relates to improvements in producing fire-proof walls, ceilings, or coatings of the same; and it consists of the employment of textile fabric for retaining the fire-proof mortar or plaster in the open spaces of the metal structure until the mortar or plaster has entirely set or hardened.

It has been proved by experience that in producing fire-proof walls or ceilings by the employment of a simple narrow meshy wire net-work, which has been hitherto embedded within layers of mortar or plaster for retaining the latter within the open spaces of the structure, no satisfactory results have been obtained. This is due to the circumstance that the greatest attention must be paid in stretching the wire-gauze to the necessary extent when employed for ceilings, and, furthermore, the employment of such narrow meshy and strong wire-gauze will considerably increase the cost of the production of fire-proof walls and ceilings.

To overcome these disadvantages is the object of my present invention, and the manner to carry the same into effect will be understood by means of the accompanying drawings, in which—

Figure 1 is a section of a fire-proof partition made according to my invention. Fig. 2 shows a modification of the same. Fig. 3 illustrates a textile fabric provided with loops for the reception of single bars or wires to form a subordinate structure of the fire-proof partition, and Figs. 4 and 5 are two different sections of a structure provided with a fire-proof coating for a ceiling produced according to my invention.

In producing fire-proof walls, ceilings, and other partitions a textile fabric—such as linen, cotton, or jute canvas—is fastened to the structure in such a manner that the open spaces of the latter will be filled out with or without the addition of metal bars or rods *b* by the textile fabric *c*. If such a subordinate

structure of bars or rods *b* is employed, the textile fabric must be rigidly connected to same by means of wires or cords, and the fabric may be attached to such bars or rods, so as to form either a plane, Figs. 1, 3, 4, and 5, or a corrugated surface, Fig. 2. In either case a close-woven fabric is required to secure the adhesion of the mortar or plaster, which is preferably applied to the fabric as a liquid pulp by means of an ordinary mason-scoop. As soon as this primary coating of mortar or plaster is sufficiently hard so as to render the fabric quite steady I continue to throw mortar or plaster from one or both sides of the fabric until the latter and the structure are entirely embedded into the plaster. The fabric may be stretched either directly over the bars or rods *c*, which in some cases may be arranged so as to form a net-work having very wide meshes, or it may be fastened to the main structure and the metal bars or net-work connected at a certain distance apart from the fabric Fig. 3. In this case the bars or net-work may be suspended by wire loops or clamps *d*, which have to be fastened either to the main structure or they may be connected to the tissue or fabric prior to the fastening of the latter to the structure. The textile fabric is only adapted to retain the plaster or mortar within the open spaces of the structure or auxiliary metal net-work until the mortar or plaster, forming a throughout-uniform fire-proof coating, has fully set and become hard. In case of fire the textile fabric cannot destroy the plaster coating by dilatation; but it will be only carbonized, while the expansion of the bars *b* or of the metal net-work will take place only in rectilinear or nearly rectilinear direction, so that they cannot cause any destructive action upon the wall or ceiling. In some cases the textile fabric may be impregnated in the usual manner with convenient solutions—such as water-glass, chloride of calcium, alum, or the like—in order to render it also fire-proof.

Instead of using metal bars *b*, I prefer in some cases to use laths, either impregnated or not.

When using a metal net-work with wide meshes, the textile fabric may either be attached thereto or woven together with the same to permit its rolling up, that it may be

manufactured and brought in trade ready for use. The textile fabric then occupies the spaces formed by the metal net-work, in order to retain the mortar or plaster while producing the walls or ceilings. Instead of attaching or weaving the textile fabric together with the metal net-work, I may attach only the loops *d*, of suitable length, to the fabric for the suspension of the bars *b*, adapted to form the subordinate structure of the fire-proof partition, which will be particularly applicable in producing fire-proof ceilings. The textile fabric provided with such loops is particularly adapted to be manufactured and brought in trade ready for use.

Having now particularly described my said invention, what I claim, and desire to secure by Letters Patent, is—

1. As an improvement in fire-proof walls, ceilings, and other partitions, the combination of a textile fabric, a subordinate structure formed of bars, laths, metal net-work or the like, and a coating of fire-proof material, substantially as set forth. 20

2. The combination of a metal net-work 25 with a tissue of fibrous material and with a mortar coating applied to the same, substantially as specified.

In testimony that I claim the foregoing as my invention I have signed my name, in presence of two witnesses, this 25th day of March, 1890. 30

CARL FRIEDRICH WILHELM DÖHRING.
